Application September 11, 1951, Serial No. 16,606

Term of patent 14 years

(Cl. D58—2)

To all whom it may concern:

Be it known that we, Lillian Levy and Charlotte Rosenfield, citizens of the United States of America, residing respectively at 2120 Dexter Avenue and 9511 Bruce Drive, Silver Spring, in the county of Montgomery and the State of Maryland, have invented a new, original, and ornamental Design for a Bag or Similar Article, of which the following is a specification, reference being had to the accompanying drawing, forming a part thereof.

In the drawing:

The drawing has been shaded to show a contrasted appearance.

This application is a continuation-in-part of our application No. D. 12,508, filed October 10, 1950.

We claim:

The ornamental design for a bag or similar article, as shown and described.

LILLIAN LEVY.
CHARLOTTE ROSENFIELD.
